United States Patent Office.

LEVI MILLER, OF JOHNSVILLE, OHIO.

Letters Patent No. 78,389, dated May 26, 1868.

IMPROVEMENT IN GATES.

The Schedule referred to in these Letters Patent and making part of the same.

TO ALL WHOM IT MAY CONCERN:

Be it known that I, LEVI MILLER, of Johnsville, in the county of Montgomery, in the State of Ohio, have invented a new and improved Gate; and I do hereby declare that the following is a full and exact description thereof, reference being had to the accompanying drawing, and to the letters of reference marked thereon.

The nature of my invention consists in constructing a farm-gate in two parts, the lower section of which being adjustable vertically.

To enable others skilled in the art to make and use my invention, I will proceed to describe its construction and operation.

The figure represents a perspective view of the gate.

The gate is constructed in two parts, the upper of which has the boards 1, 2, and 3 attached to the upright pieces D and E. The under section of the gate is constructed by the boards 4 and 5 being attached, at their ends, to the pieces G and H, which pieces slide within the clasps B, and to the centre of these boards is attached the upright piece A, which moves within the guide C. A series of holes, o o o o, is made in this upright, and a hole is made through the gate, in which a pin, m, is used, and by this means the lower part of the gate is held at the desired elevation. To the back of the gate is attached a brace, F, extending from one upright to the other. At n a handle is attached, by which to elevate the lower section; the object of this invention being to effect the elevation of the lower part of the gate when it is necessary, as in case of snow or other obstructions, without raising the entire gate.

What I claim as my invention, and desire to secure by Letters Patent, is—

The construction of a farm-gate in the manner as herein described and represented.
